UNITED STATES PATENT OFFICE.

GEORGE F. WELLS, OF SAN FRANCISCO, CALIFORNIA.

DESIGN FOR A WAFFLE IRON.

Application filed February 27, 1922. Serial No. 921. Term of patent 7 years.

To all whom it may concern:

Be it known that I, GEORGE F. WELLS, a citizen of the United States, and a resident of the city and county of San Francisco, State of California, have invented a new, original, and ornamental Design for a Waffle Iron, of which the following is a specification, reference being had to the accompanying drawings, forming part thereof.

Figure 1 is a plan view of a waffle iron.

Fig. 2 is a side elevation, and

Fig. 3 is an end elevation looking toward the hinged side of the waffle iron, respectively illustrating my new design.

I claim:

The ornamental design for a waffle iron, substantially as shown.

GEORGE F. WELLS.
